(57) **CLAIM**

The ornamental design for an air intake grille, as shown and described.

DESCRIPTION

FIG. 1 is a perspective view of an air intake grille according to our new design;

FIG. 2 is a front view of the air intake grille of FIG. 1;

FIG. 3 is a top view of the air intake grille of FIG. 1; and,

FIG. 4 is a bottom view of the air intake grille of FIG. 1.

The rear of the air intake grille is unornamented.

The broken lines shown in FIGS. 3 and 4 form no part of the claimed design.

FIGS. 1-4 illustrate a first embodiment of our novel design suitable for use on a first side of a vehicle. Our novel design also includes a second embodiment suitable for use on a second side of a vehicle, which is mirror symmetrical to FIGS. 1-4 and therefore not separately illustrated.
